United States Patent Office.

THOMAS CROSSLEY, OF BRIDGEPORT, CONNECTICUT.

Letters Patent No. 71,460, dated November 26, 1867.

IMPROVEMENT IN CANE AND LAMP COMBINED.

The Schedule referred to in these Letters Patent and making part of the same.

TO ALL WHOM IT MAY CONCERN:

Be it known that I, THOMAS CROSSLEY, of Bridgeport, in the county of Fairfield, and State of Connecticut, have invented a new and useful Improvement in Portable Lamps; and I do hereby declare that the following is a full, clear, and exact description of the same, reference being had to the annexed drawings, making part of this specification, in which—

Figure 1 is a side elevation, with parts represented as broken away, and

Figure 2 is a vertical section.

The same letters are employed in both figures in referring to identical parts.

The object of my invention is the insertion of a lamp into canes, crutches, umbrella-handles, whips, and other analogous portable articles usually carried in the hand.

A represents the shaft of a cane, the handle of an umbrella, &c., formed in two pieces, A and A', screwed together. In the part A is inserted an oil-receptacle, B, which contains the oil, burning-fluid, or other material used, and the wick, which passes through the wick-tube C. D is a cap, which covers the wick-tube when the lamp is not lighted. This may be a separate piece, or constructed so as to form part of the piece A'.

The lamp may be burned with the piece A' removed, or the latter may be constructed with suitable transparent material surrounding the flame or part thereof, and with the requisite ventilation for the support of the flame, furnished by making the piece A' in the form of a pipe, open above, and with air-holes below the flame.

The cap D should be compressed by an India-rubber spring holding it firmly on the wick-tube, on which it fits tightly, so as to prevent all leakage.

The ferrule E may be made to screw off, leaving a spike exposed; which, projecting from the bottom of the cane, may be stuck into the floor, to support the lamp.

What I claim as my invention, and desire to secure by Letters Patent, is—

A cane, staff, crutch, umbrella-handle, or other analogous portable article, constructed in two parts, A and A', and enclosing the oil-receptacle B and wick-tube C in one part, and the cap D and compressing-spring, bearing against the latter in the other part, said parts being arranged substantially as set forth.

In testimony whereof I have signed my name to this specification in the presence of two subscribing witnesses.

THOMAS CROSSLEY.

Witnesses:

AMOS S. TREAT,

H. T. BLAKE.
